United States Patent Office

Des. 208,293
Patented Aug. 15, 1967

208,293

BUILDING

George L. Hay, 10517 Wyatt St.,
Dallas, Tex. 75218

Filed Dec. 31, 1964, Ser. No. 83,243

Term of patent 14 years

(Cl. D13—1)

FIG.1

FIG. 2

FIG.3

FIGURE 1 is an isometric view of one form of the building, in accordance with the present invention;

FIGURE 2 is a side elevational view of the building of the present invention; and

FIGURE 3 is an isometric view of the other side and end of the building showing another form of the present invention, the difference residing in the cross-sectional shape of the building.

I claim:

The ornamental design for a building, as shown and described.
